UNITED STATES PATENT OFFICE

1,989,529

DETACHABLE LAMP DEVICE

William A. Ready, Brookline, Mass.

Original application May 29, 1928, Serial No. 281,561. Divided and this application July 22, 1929, Serial No. 380,134

4 Claims. (Cl. 173—339)

My invention aims to provide improvements in quick detachable lamp devices particularly, though not exclusively, for use in connection with illumination of radio and like dials.

5 In the drawing which illustrates a preferred embodiment of my invention:—

Figure 1 shows a front elevation of the dial mechanism as it appears when attached to the panel of a radio receiver;

10 Fig. 2 is a section taken through the panel and showing parts of the device in cross-section and parts in elevation;

Fig. 3 is a detail view of the rear of the lamp mounting and the support therefor; and

15 Fig. 4 is a section taken on the line 4—4 of Fig. 3, the lamp being shown in elevation.

This application is a division of my application Serial No. 281,561, filed May 29, 1928, which has issued into United States Letters Patent No.

20 1,751,658, dated March 25th, 1930.

As the invention pertaining to this application is directed primarily to a quick detachable lamp device for illumination of dials of radio and like apparatus, I shall not describe in detail the particular dial shown. The drum type dial 1 is mounted in back of a panel 2 and a portion thereof is exposed through the opening 3 in the panel, as shown in Figure 1.

The dial 1 may be illuminated on its face or, 30 if it is made of translucent material, through it as desired. In the illustrative embodiment of my invention I have shown the dial illuminated upon its face by means of a quick detachable lamp unit mounted as shown in Fig. 2 and more fully described in the application from which this is divided.

The quick detachable lamp unit selected for illustration has a socket 4 into which is threaded an incandescent lamp 5 (Fig. 4) which makes contact with the terminals 6 and 7 (Figs. 3 and 4) for completing an electric circuit through the lamp. To provide for quick attachment or removal of the unit for changing the lamp I have secured a rubber ring or washer 8 to the socket

45 4. This ring or washer is flexible and has a pair of yieldable flanges 9 which engage the opposite faces of the bracket 10 and hold the unit in the desired position. With this or a similar construction employing two flanges which may make frictional contact with the bracket 10 I can remove or attach the unit at will without the use of any instruments and without the necessity of complicated attachment of any part of the entire lamp unit to the supporting means. The device is self-contained and is assembled at the

point of manufacture. It may be used for illumination of dials already in use because usually there is some structure which will permit attachment of the flexible means at a point where the lamp may be effective for illumination of a dial.

5 While I have illustrated and described my invention somewhat specifically, I do not wish to be limited thereby and reference is made to the following claims to indicate the scope of my invention.

I claim:

1. An illuminated radio dial installation or the like having, in combination, a supporting member having a relatively thin edge portion defining a marginal side thereof, a lamp socket having provision for direct attachment thereto of the leads for energizing the lamp carried thereby, means for removably securing said lamp socket to said edge portion by lateral movement toward said marginal side of said support, said means comprising an attaching member of resilient material carried by said socket to form a unit therewith, said attaching member being formed with a laterally extending slot opening on the exterior thereof to provide a pair of resilient, laterally extending flanges for removably and frictionally gripping the opposite sides of said edge portion of said supporting member, whereby said unit may be readily attached to and removed from the edge portion of said supporting member while said leads are attached to said socket.

2. An illuminated radio dial installation or the like having, in combination, a supporting member having a relatively thin edge portion defining a marginal side thereof, a lamp socket having a shell of conductive material adapted to receive the base of a lamp, said lamp socket having provision for direct connection thereto of leads for energizing said lamp, means for removably securing said lamp socket to said edge portion by lateral movement toward said marginal side of said support, said means comprising an insulating and attaching member of resilient material surrounding said shell and directly carried thereby to form a unit therewith, said insulating and attaching member formed with a relatively deep slot opening on its exterior surface to provide a pair of resilient, laterally extending flanges for removably and frictionally gripping the opposite sides of said edge portion of said supporting member, whereby said unit may be readily attached to and removed from the edge of said supporting member while said leads are attached to said socket.

3. An illuminated radio dial installation or the

like having, in combination, a supporting member having a relatively thin edge portion formed with a notch opening on said edge, a lamp socket adapted to be received within said notch for positioning said socket relative to said member, said socket having provision for direct attachment thereto of the leads for energizing the lamp carried thereby, an attaching member of resilient material carried by said socket to form a unit therewith, said attaching member surrounding said socket and being formed with a circumferential slot to provide a pair of resilient, laterally extending, circumferential flanges for removably and frictionally gripping the opposite sides of said edge portion of said supporting member, whereby said unit may be readily attached to and removed from the edge portion of said supporting

member and said socket may be frictionally held in different positions of rotative adjustment axially thereof within said notch.

4. A lamp socket assembly adapted to be attached to and removed from a relatively thin edge portion of a support by lateral movement toward and away from said support comprising a lamp socket having provision for direct attachment thereto of the energizing leads for the lamp carried thereby, said socket including an attaching member of resilient material, said attaching member being formed with a laterally extending slot opening on the exterior thereof to provide a pair of resilient, laterally extending flanges for removably and frictionally gripping the opposite sides of the edge portion of the support. 15

WILLIAM A. READY.
